UNITED STATES PATENT OFFICE

2,358,705

ARCH HOOK

Henry Gustafson, Astoria, Oreg.

Application July 31, 1942, Serial No. 453,141

6 Claims. (Cl. 24—123)

This invention relates to arch hooks for log chockers or cables.

An object of this invention is to provide an improved coupler for a chocker or cable engaging about a log during the dragging of the log which will eliminate any twisting of the chocker or cable.

Another object of this invention is to provide a swivel coupler which will permit rotation of the log without torsional or twisting strain on the chocker or cable.

A further object of this invention is to provide a swivel coupler of this kind which will facilitate the connection of the chocker or draft cable with the pulling member and provide an economy in the amount of cable necessary to produce the chocker.

A further object of this invention is to provide a swivel coupler which includes a slotted body, a clevis swivelly connected to the body, and an improved means for releasably locking an end of a cable in a slot so that the cable cannot accidentally become released during the dragging of the log.

With the foregoing objects in view, and others which may hereinafter more fully appear, the invention consists of the novel construction combination and arrangement of parts as will be more specifically referred to and illustrated in the accompanying drawing, but it is to be understood that changes, variations and modifications may be resorted to which fall within the scope of the invention as claimed.

In the drawing:

Figure 1 is a detail side elevation of an arch hook constructed according to an embodiment of this invention.

Figure 2 is a fragmentary sectional view, partly in elevation, taken on the line 2—2 of Figure 1.

Figure 3 is a section taken on the line 3—3 of Figure 1.

Figure 4 is a sectional view, taken on the line 4—4 of Figure 1.

Figure 5 is a sectional view, taken on the line 5—5 of Figure 4.

Referring to the drawing the numeral 10 designates generally an elongated body which is provided lengthwise thereof with a bore or opening 11. A shank 12 is rotatably or swivelly mounted in the bore 11 and is provided at its forward end with a head 13 engaging the forward end of the body 10 so as to hold the shank 12 against endwise movement in one direction. The head 13 may be formed by upsetting the adjacent end of the shank 12, or by any other suitable means. The shank 12, at its rear end, is provided with an

integral head 14, of annular construction, which has formed integral therewith, an eye 15. A clevis 16 is pivotally mounted on a clevis pin 17 extending through the arms of the clevis 16, and through the eye 15. The body 10 is formed lengthwise thereof with a pair of lengthwise channels or sockets 18 which terminate rearwardly of the forward end of the body 10 and open through the rear end thereof. The body 10 is also formed with an elongated lengthwise slot 19 communicating with the socket 18. The body 10 is also formed at the rear end of the socket 18, with a passage 20 extending through the rear end of the slot 19, so that the enlarged end 21 of a flexible draft member or cable 22 may be extended through the passage 20 and this enlarged end then moved forwardly to the forward end of the socket 18. The enlargement 21 may be in the form of a knot or ferrule which is fixed to the adjacent end of the flexible member 22 so that when the enlargement 21 is within the socket 18 the flexible member 22 will be firmly secured to the body 10. There are shown two of these sockets 18 in the body 10, but it will be understood that there may be any desired number of these sockets, depending upon the number of chockers or cables which are to be connected to the coupling device herein disclosed.

In order to provide a means whereby the flexible member 22 will have the enlargement 21 thereof locked in the socket 18, I have provided a rotatable locking member 23 which is rotatable on the shank 12 and interposed between the head 14 and the rear end of the body 10. The rotatable locking member 23 is releasably held against rotation by means of a spring-pressed pin 24. The pin 24 is slidable in a passage 25 which is formed in the body 10, and opens through the rear end thereof outwardly from the bore 18. The pin 24 is urged rearwardly to a locking position by means of a spring 26 and in order to limit the movement of the pin 24 this pin has been provided with an annular channel or groove 27 in which a set screw 28 loosely engages. The set screw 28 is threaded in the body 10, across the opening or passage 25, and normally abuts against the forward end of the groove 27. The rear end of the pin 24 is normally disposed rearwardly of the rear end of the body 10, and is engageable in a selected one of a pair of notches 29 which are formed in the locking washer 23.

The flexible member 22 is adapted to have a hook 30 secured to the forward end thereof, and this hook is adapted to engage the flexible member 22 rearwardly of the forward end thereof,

when the flexible member 22 is wrapped about a log thereby forming a slip-loop which is tightened when a pulling force is exerted on the coupling member, including the body 10 and the clevis 16.

With a construction as hereinbefore described, the log may rotate independently of the draft device, as the log is being dragged along the ground and by reason of the rotatable mounting of the body 10 on the shank 12, the clevis 16 will not rotate with the rotation of the log and of the body 10. Furthermore, by providing the body 10 with the longitudinal sockets 18, the chockers or flexible members 22 may be formed out of a length of cable substantially shorter than is possible with the coupling devices at present in use. Furthermore, by providing the locking member 23 at the rear ends of the sockets 18, the flexible members 22 or chockers will not accidentally become disengaged from the coupling device as in order to remove the enlargement 21 from the socket 18 it is necessary to depress the pin 24 engaging in one of the notches 29, and then shift the locking member 23 so that the desired notch 29 thereof is in registry with the rear end of the socket 18. The passage 20 is sufficiently small in size so that the enlargement 21 cannot be removed from the socket 18 until the locking member 23 has one notch 29 thereof in registry with the selected socket 18.

What I claim is:

1. In an arch hook for log chockers comprising an elongated body formed with an elongated lengthwise socket and a lengthwise slot opening into said socket, a shank member rotatably engaging in said body, a head on one end of said shank, an eye carried by said head, a clevis rockably engaging said eye, a locking member rotatable on said shank between said body and said head, said locking member formed with a notch for registry with said socket whereby an enlargement on said chocker may be released from said log socket, and releasable means carried by said body for holding said locking member in locked position.

2. In an arch hook comprising an elongated body formed with an elongated lengthwise socket and a lengthwise slot opening into said socket, a shank member rotatably engaging in said body, a head on one end of said shank, an eye

carried by said head, a clevis rockably engaging said eye, a locking member rotatable on said shank between said body and said head, said locking member formed with a notch for registry with said socket whereby a log chocker may be released from said socket, and a spring pressed locking pin carried by said body engageable in said notch for holding said locking member in locking position.

3. In an arch hook comprising an elongated body formed with an elongated lengthwise socket and a lengthwise slot opening into said socket, a shank member rotatably engaging in said body, a head on one end of said shank, an eye carried by said head, a clevis rockably engaging said eye, a locking member rotatable on said shank between said body and said head, said locking member formed with a notch for registry with said socket whereby a log chocker may be released from said socket, a spring pressed locking pin carried by said body engageable in said notch for holding said locking member in locking position, said pin having an elongated peripheral groove, and a screw carried by said body extending into said groove to thereby limit the endwise movement of said pin.

4. An arch hook for log chockers including a swivel coupler for connection with a pulling member whereby the log may rotate without torsional strain on said chocker, said coupler including a slotted body and a clevis swivelly connected to said body, and means carried by said body for releasably locking an end of a cable in a slot to hold the cable against release during the dragging of the log.

5. An arch hook comprising a body formed with a socket and a slot opening into said socket, a shank member rotatably engaging in said body, a locking member rotatable on said shank, and means carried by said shank member for holding said locking member in locking position.

6. An arch hook comprising a body formed with a socket and a slot opening into said socket, a shank member rotatably engaging in said body, a locking member rotatable on said shank, and means carried by said shank member for holding said locking member in locking position, said means including a spring pressed locking pin carried by said socket and a notched keeper carried by said shank for engagement with said pin.

HENRY GUSTAFSON.
